UNITED STATES PATENT OFFICE.

THOMAS E. MURRAY, JR., OF NEW YORK, AND WILLIAM C. BLACKWOOD, OF ELMHURST, NEW YORK; SAID BLACKWOOD ASSIGNOR, BY MESNE ASSIGNMENTS, TO SAID THOMAS E. MURRAY, JR.

SWITCH AND FUSE MECHANISM.

Application filed September 9, 1922. Serial No. 587,189.

The invention relates to an electric switch with a fuse and casing therefor and it is designed to permit introduction of a fuse from the outside of the box to take the place of one which has been blown out, and is designed to have various other advantages referred to in detail hereinafter. In some respects the invention is an improvement on the mechanism covered in the application of Murray No. 556,818, filed April 26th, 1922.

The accompanying drawings illustrate embodiments of the invention.

Fig. 1 is a side elevation of a complete apparatus;

Fig. 2 is a plan of the principal parts with the box open;

Fig. 3 is a perspective view of one of the fuses and adjacent parts with the box in vertical section;

Fig. 4 is a plan and Fig. 5 is a perspective view of another embodiment of the invention;

Fig. 6 is a vertical section of a third embodiment of the invention;

Fig. 7 is a plan of certain parts of Fig. 6;

Fig. 8 is a vertical section (partly in elevation) of another apparatus embodying the invention;

Fig. 9 is a front elevation of a part of the same;

Fig. 10 is a horizontal section of one of the fuse carriers;

Fig. 11 is a group of views showing the separate parts of a fuse carrier.

Referring first to the apparatus of Figs. 1, 2 and 3, the casing is provided with side walls 1 and rear end wall 2 and a cover 3 with an elevated central portion 4 to form a pocket for the switch blades within the box when the blades are turned upward. The base of the box is provided with an extension 5 at one end for mounting the meter.

The switch blades 6 are pivoted at one end on supporting posts 7 and adapted to engage contacts 8 at their opposite ends or to be swung up out of engagement with said contacts. They are connected to each other by an insulated cross-bar 9 which carries a hook 10 for lifting them by hand when the box is open. The hook 10 has its rear end bent around an offset portion 11 of a shaft which is pivoted at its opposite ends as shown at 12 and 13 in the side walls of the box; the end 13 carrying an arm or lever 14 by which

the shaft can be turned so as to swing up 55 the offset portion 11 and with it the two switch blades. The switch operating arm 14 is limited in its opening and closing movement by means of lugs 15 and 16 on the outside of the box.

The mechanism thus far described is a common arrangement for operating a switch from the outside of the casing, so that the latter can be locked and opened by the electric company only, whereas the switch can 60 be controlled by the user of the current.

We propose to apply to this and to any other usual or suitable mechanism means for introducing a fuse or fuses, or for withdrawing a burnt out fuse from the circuit 70 and substituting a new one, also without access to the inside of the box or to the other parts of the mechanism. We prefer in addition to so arrange the parts as to require 75 the operator to disconnect the fuse socket or terminals from the circuit when a fuse is to be inserted or a new one substituted for an old one, so as to provide the maximum of safety against a shock to the operator.

These results we may accomplish by the 80 use of a multiple-fuse carrier so designed and positioned that it can be manipulated from the outside of the box, or while the other parts of the mechanism are inaccessible, to remove a burnt fuse from the circuit 85 and substitute a new one therefor. Various multiple fuse carriers are known and may be used with our invention.

We have illustrated in this connection a common style of multiple fuse carrier of 90 which the contacts are shown in Fig. 10 and the separate parts grouped together in Fig. 11. The shell 17 carries a contact ring 18 which screws into the fuse socket of the apparatus and makes contact with the side 95 thereof, while the end button 19 makes contact with the center point at the bottom of the socket. A plug 20 fits into the shell 17 and carries, set in vertical grooves around it, a number of fuses 21 one of which bears 100 against a terminal 22 which is connected with the ring 18. The plug 20 may be turned, the successive contacts 21 snapping into engagement with the terminal 22, the latter being pressed forward by a spring for 105 the purpose. The plug has a shoulder or head 23 which bears on the edge of the shell 17 and has an oblong projection 24 by which

it may be seized and turned to bring successive fuses into operative position. The plug is fastened down by a ferrule 25 which bears on top of the plug and screws on to the outside of the contact carrying shell 17.

In each of the two circuits shown in Figs. 2 and 3 there is a socket 26 carrying one of these multiple fuse carriers with a thumb piece or handle 24 of sufficient height to project through an opening 27 in the cover of the box which surrounds the same closely.

The stem or handle 24 carries at a point within the box a plate 28 with a number of notches 29 in its edge corresponding in angular position with the several fuses carried thereby. The offset portion 11 of the shaft by which the switch is operated carries projections 30 adapted to fit in the recesses 29 and thus to prevent rotation of the plates 28 and of the fuse carrier. This locking engagement occurs when the switches are closed as in Fig. 3. When the switch is opened, however, the projections 30 are withdrawn upward from the notched plates 28 and the fuse carriers can be turned by means of their squared stems projecting through or accessible through openings in the casing. Thus we have a double safety feature in that the operator changes a fuse with the casing closed and that the fuse socket with its terminals is disconnected at the time by the opening of the switches.

In Figs. 4 and 5 a similar result is obtained by covering the stem or operating handle of the fuse carrier and permitting the uncovering of the latter only when the switch is open. In this construction the switch blades 6 are swung up by means of a shaft 31 having a handle on the outside with a lateral pin 33 adapted to lie in a notch 34 in a flange 35 which projects upward from a plate 36. This plate is mounted to turn about the vertical axis of the box and has openings 37 adapted in one position to overlie the stems 24 of the fuse carriers so as to permit operation of the latter from the outside, or in the alternative position (as in Fig. 4) to be out of register with such stems so as to prevent access thereto. In this position the locking pin 33 of the handle holds the plate against rotation as long as the handle is down and the switch closed. Only when the handle is raised to open the switch can the plate be turned to position for access to the fuse carriers.

Figs. 6 and 7 illustrate an apparatus using a rotary switch of the type shown in the Murray application previously referred to. The cross-bar 37 is mounted on a shaft 38 which carries certain switch arms, not illustrated, at its lower end. The cross-bar 37 is surrounded by a flange 39. The cross-bar carries also certain fuse sockets 40, and in each of these is a multiple fuse carrier 65 which we have designated generally by the

numeral 41 and which has its squared stem 24 at the upper end. The cover 42 of the casing is pivoted at one side as illustrated and carries on its inner face a circular plate 43 pivotally mounted and provided with a pair of depending conical flanges 44 adapted to fit into the ends of the flange 39 of the cross-bar. The projections 44 are again bent upward at their inner edges and form a flange 45 overlying all of the multiple fuses carrier except the stem thereof. The plate 43 is supported by a pivot 46 from the cover, and can be turned about this pivot by a projecting handle 43^a. When the cover is down, the projections 44 fit within the flange 39, and the turning of the plate 43 will turn the shaft 38 and the switch to the open or closed position. The cover is provided with a pair of openings 47 adapted to give access to the stems 24 of the fuse carriers when the latter, and the cross-bar 37, are in the position in which the switch is open. While the switch is closed, the stems 24 of the fuse carriers are covered by the solid portion of the cover, and no change of fuses can be accomplished.

Figs. 8 and 9 illustrate the application of the invention to what we call a plunger device. A block 48 carries one or more fuse terminals 41 with stems 24 passing through an opening in a flange 49 of a casing which surrounds the block 48 and which can be thrust down into the box 50 or can be pulled up out of the box by means of a handle 51. Blades 52 and 53, insulated from each other, are carried by the plunger and adapted when the latter is down to close the circuit through the terminals 54 and 55 respectively. When the switch is opened by lifting the plunger, then the stems of the fuse carriers become accessible. Otherwise they are within the casing and inaccessible.

The flange 49 overlies the head of the fuse carrier so that the latter cannot be removed to give access to the fuse terminals inside, but can be turned to introduce a new fuse. Not only is the remainder of the switch mechanism and the connections thereof enclosed in the casing and inaccessible, but even the fuse terminals themselves are inaccessible. In the previous figures also the fuse carrier is held against removal. When all the fuses in a carrier have been used in succession it is necessary to call upon the company to open the casing and introduce a new fuse carrier.

The notched plates 28, Fig. 2, are fastened on flanges on the stems 24 by means of screws passing through annular slots 56; so that the plates may be set to register with the projections 30 when the fuses are in circuit.

The fuses of the mechanism, including those first in circuit and the one or more extra fuses to be substituted therefor, are

not necessarily carried all by a single carrier, as illustrated, and moved by a single operating device on the outside; though this arrangement is preferable for simplicity of construction and operation.

The purpose of having the switch with its terminals enclosed within the casing is to primarily prevent access to the switch terminals by unauthorized persons. It is not only to cut off the outside circuit when a new fuse is to be introduced, but to prevent access to the terminals within the casing when the meter is disconnected by the opening of the switch. The switch can be opened and closed without operation of the fuse, the means for operating the switch being operatively independent of the fuse carrier.

Though we have described with great particularity of detail certain embodiments of our invention, yet it is not to be understood therefrom that the invention is restricted to the particular embodiments disclosed. Various modifications thereof in detail and in the arrangement of the parts may be made by those skilled in the art without departure from the invention as defined in the following claims.

What we claim is:

1. An apparatus of the class described comprising a switch, a plug fuse shell pro-

viding a wall between the fuses and the terminals of the switch, a casing enclosing said parts and preventing access thereto and a multiple fuse carrier in said shell and having a handle accessible from the outside of the casing by which a fuse can be replaced without opening the casing.

2. The apparatus of claim 1, the multiple-fuse carrier being rotatable and having a central stem accessible from the outside of the casing for rotating the carrier.

3. The apparatus of claim 1, the fuse carrier having an operating portion extending through an opening in the cover of the casing and the switch having a separate operating portion extending through the side of the casing.

4. The apparatus of claim 1, the fuse carrier having an operating portion extending through an opening in the cover of the casing and the switch having a separate operating portion extending through the side of the casing, and said operating portions being interlocked with each other within the casing.

In witness whereof, we have hereunto signed our names.

THOMAS E. MURRAY, JR.
WILLIAM C. BLACKWOOD.
